UNITED STATES PATENT OFFICE.

HENRY B. KEIPER, OF LANCASTER, PENNSYLVANIA, ASSIGNOR OF ONE-HALF TO JOHN HERTZLER, OF SAME PLACE.

DESIGN FOR A BALL-RETAINER.

SPECIFICATION forming part of Design No. 28,868, dated June 14, 1898.

Application filed May 17, 1898. Serial No. 680,989. Term of patent 14 years.

To all whom it may concern:

Be it known that I, HENRY B. KEIPER, a citizen of the United States, residing at Lancaster, in the county of Lancaster and State 5 of Pennsylvania, have invented and produced a new and original Design for Ball-Retainers; and I do hereby declare the following to be a full, clear, and exact description of the invention, such as will enable others skilled in 10 the art to which it appertains to make and use the same.

The present design is for a cage or retainer employed in bearings for holding a cluster of balls, and the design is characterized by the 15 following features: An annular cupped base or ring, a series of standards springing from the inner edge of said base, and flanges on the outer ends of said standards, said flanges projecting outwardly at right angles to the 20 standards and being of sectoral or segmental form.

In the accompanying drawings, which illustrate the design and form part of this specification, Figure 1 represents in perspective a 25 ball-retainer of my improved design. Fig. 2

represents the same in plan, and Fig. 3 is a cross-section on line III III of Fig. 2.

Referring to said drawings, the letter *a* designates the annular base or ring, which is curvilinear in cross-section or cupped and from 30 the inner edge of which spring the standards *b* in considerable number. These standards are separated by approximately U-shaped spaces *b'*, and on their outer ends flanges *c* are formed, said flanges flaring outwardly, 35 which gives them a sectoral or segmental appearance. The confronting edges of these flanges are slightly concaved, as shown at *c'* in Fig. 2, while their outer edges are embraced in a circle. 40

What I claim is—

The design for a ball-retainer substantially as shown and described.

In testimony whereof I affix my signature in presence of two witnesses.

HENRY B. KEIPER.
